[57] CLAIM

The ornamental design for a transmitter for missing person location, substantially as shown and described.

DESCRIPTION

FIG. 1 is a bottom view of a transmitter for missing person location showing my new design;

FIG. 2 is a top plan view thereof;

FIG. 3 is a side elevational view, the opposite side being a mirror image thereof;

FIG. 4 is an end elevational view, the opposite end being a mirror image thereof.
